(74) Attorney, Agent, or Firm—Brinks Hofer Gilson & Lione

(57) **CLAIM**

The ornamental design for a mobile phone, as shown and described.

DESCRIPTION

FIG. 1 is a top perspective view of a mobile phone of the present invention;

FIG. 2 is a front view thereof;

FIG. 3 is a first side view thereof;

FIG. 4 is a top view thereof;

FIG. 5 is a second side view thereof;

FIG. 6 is a rear view thereof; and,

FIG. 7 is a bottom view thereof.
